UNITED STATES PATENT OFFICE.

CHARLES N. CORYELL, OF MAMARONECK, NEW YORK, ASSIGNOR TO SCOVILL MANUFACTURING COMPANY, OF WATERBURY, CONNECTICUT, A CORPORATION OF CONNECTICUT.

SECTIONAL-WALL VANITY CASE.

Application filed September 8, 1926. Serial No. 134,176.

This invention relates to small metallic containers, and more particularly to vanity cases which are commonly used for carrying small articles, like powder compacts and 5 mirrors, in a readily accessible manner.

Vanity cases which are frequently carried about the person, should preferably be designed to occupy a minimum amount of space, and should present a neat and pleasing 10 appearance. Furthermore, it is desirable that the powder compact be readily removable to facilitate replacement when the supply becomes exhausted.

This invention relates particularly to a 15 case in which the powder compact is mounted in a detachable and removable metallic base plate, preferably dish shaped, that is so assembled as to become an integral and essential part of the wall of the case itself.

20 The metallic base plate is suitably finished on the outside to correspond with the outside finish of the case, and is firmly and removably secured in a cover ring to form in connection therewith a complete cover section.

25 By thus designing the compact container to form a portion of the cover section the total thickness of the cover may be reduced to that of one piece of metal, and the size of the complete case correspondingly reduced.

30 The invention further relates to a simplified method of fastening the compact in the case by means of the pintle wire which passes through the hinge knuckle and is extended around the cover to overlie the compact at 35 one or more points peripherally spaced from the hinge knuckle, whereby the compact is rigidly and removably secured in place.

This invention still further relates to a 40 simplified method of imparting a finish to a vanity case by forming portions of the outside surface of different materials or by plating various parts of the case itself with different metals.

This invention still further relates to a 45 vanity case of simplified and improved construction, as hereinafter set forth.

50 Although the novel features which are believed to be characteristic of this invention will be pointed out with particularity in the claims appended hereto, the invention itself, as to its objects and advantages, the manner of its organization and the mode of its ap-

plication, may be better understood by referring to the following description taken in connection with the accompanying drawings 55 forming a part thereof, in which:

Fig. 1 is a plan view of the vanity case in fully open position;

Fig. 2 is a broken section taken on the line 2-2 of Fig. 1;

Fig. 3 is a broken section taken on the line 3-3 of Fig. 1; and

Fig. 4 is a broken sectional view showing the compact partly removed.

Referring to the drawings more in detail 65 the case comprises a pair of cover sections 10, 11, which for convenience of description will be called the cover member and base member respectively. The base member 11 is provided with a tongue 12 bent over upon 70 itself to provide a hinge knuckle. Pintle wire 13, passing through this hinge knuckle is extended substantially around the cover section 10, and internally thereof and is secured in beading 14 formed on said cover. 75 The pintle wire thus serves as a connecting means for the two covers and also strengthens the case by completely surrounding it. The pintle wire 13 is further provided with an indentation 15 at a point diametrically 80 opposite the hinge for the purpose to be hereinafter described. Resilient rim 16 formed on base member 11 is adapted to enter and firmly seat in the beading 14 on the cover member when the case is in a 85 closed position. A pair of pressed projections 17 on rim 16 cooperate with the beading 14 to form a catch for holding the case closed. The rim is cut away and bent back to form a flange 18 at a point diametrically 90 opposite the hinge knuckle 12. This provides a convenient finger hold for opening the case and also allows sufficient space for the indented portion of the pintle wire when the case is closed.

95 The powder compact 19 carried in metallic dished member 20, is suitably shaped to seat in annular cover member 10 and, when in the position shown in Fig. 2, forms in connection with the annular member the 100 complete cover section. The member 20 is secured in position by the hinge knuckle 12 and indentation 15 on the pintle wire 13 overlying the compact. It may be inserted

as shown in Fig. 4 by being passed under the hinge knuckle and then pressed past the indentation 15 of the pintle wire.

The mirror 21 placed on pad 22 if desired, 5 is secured to the bezel 23 which is frictionally engaged by the rim 16 and held in position thereby. The rim 16, at the position nearest the hinge, is inclined to more firmly 10 secure the bezel in place and to allow free movement of that portion past flange 13. The bezel 23 is provided with an indented portion 24 to allow it to fit snugly over flange 12.

By means of the construction above described 15 the powder compact may be readily removed and replaced. The back of base member 20 may be given a design to match that of the remainder of the case or it may be formed of a different metal. It is frequently 20 desirable to form a vanity case of a relatively cheap base metal and impart the final finish by plating the base with a more expensive material such as gold or silver. Should the covers be constructed of 25 one piece it would be extremely difficult to plate different portions with different metals. By assembling the case as herein described, however, this difficulty is avoided as the annular cover portion may be plated with one 30 metal and the central compact portion may be plated separately with a different material in accordance with the selected design. Since the annular member forms a part of the permanent case and the central portion 35 containing the compact is to be discarded when the contents become exhausted, the latter may be made of a cheaper material or plated with a cheaper metal than the case itself.

The case above described may be made extremely thin as only one thickness of metal is required to form the case and hold the powder compact. The construction is inexpensive to manufacture, and light in weight, as no extra 45 parts are required to secure the removable compact, the pintle wire serving that purpose as well as strengthening the case and forming a hinge. The bezel overlying the bent flange 12 imparts strength to the hinge member and prevents it from bending during use.

The removable portion has been herein described as a powder compact but it may take the form of a rouge cake or both parts of the case may be constructed in the same manner and one used for rouge and the other for powder or any similar article.

Although this invention has been shown and described as applied to a particular form 60 of vanity case it is not to be limited thereto, but the invention is to be defined in accordance with the scope of the following claims.

What is claimed:

1. In a box, a cover comprising a ring member and a central member, said members

each forming a portion of the wall of said cover, a co-operating section, means for separably connecting said ring member and section including an independent element, and means for detachably securing said central member to said ring member including said independent element. 70

2. In a box, a cover comprising a plurality of members detachably connected together, 75 said members each forming a portion of the wall of said cover, a co-operating section, means for separably connecting said cover and section including an independent element, and means for detachably securing said members together including said independent element. 80

3. In a box, a cover comprising a ring member and a central member, said members each forming a portion of the wall of said cover, a co-operating section, separably connected to said cover, said ring member having a seat for said central member and a flange, a wire spring retained by said flange and holding said central member in said seat. 85

4. In a vanity case, a pair of cover sections, a hinge knuckle on one of said sections, the other of said sections comprising an annular member with a seat and a central member detachably secured therein, a beading on said annular member and a pintle wire extending through said hinge knuckle and seated in said beading, said pintle wire having a portion overlying said central member, and thereby to secure it in 95 said seat, said central member forming an outside wall of the cover section. 100

5. A compact container comprising a detachable holder for a compact forming part of the outer surface of the container, a separate frame detachably secured to the holder and provided with a flange to form a meeting edge, means including a resilient member connecting the holder and the frame, and a cover member hinged to enclose the 105 compact. 110

6. A compact container comprising a detachable dished holder for a compact forming part of the outer surface of the container, a separate frame member detachably 115 secured to the holder and provided with a flange to form a meeting edge, a resilient member held in said flange for connecting the holder and the frame, and a cover member hinged to enclose the compact. 120

7. A vanity case comprising a frame member having a peripheral beading, a dished compact container removably secured in said frame, said frame member and compact container each forming a portion of the outer wall of the case, a cover member having an integral hinge knuckle and a pintle wire passing therethrough and extended substantially around said frame, said wire being seated in the beading and indented to 125 130

overlie the compact container thereby serving to form a hinge for the cover, a retaining means for the compact and a reinforcing means for the frame.

5 8. A vanity case comprising convex dish shaped covers meeting in a thin edge as compared to the maximum thickness of the case, one of said covers being made up of a plurality of separate members connected together, each member forming part of the wall of the cover, and a cosmetic compact directly compacted in one of said members.

9. In a vanity box, a convex dish shaped cover comprising a ring member having a thin inner edge and a separate convex dished center member having a thin outer edge, said members having substantially coextensive walls overlapping at said thin edges to form a lap joint, means detachably securing 20 said members together, said center member and ring member each forming part of the outer wall of the cover, a second convex dish shaped cover detachably secured to said ring member, said covers having their edges disposed in close relation when closed, and 25 a cosmetic compact molded in said center member.

10. In a vanity box, a convex dish shaped cover comprising a frame member and a 30 separate convex dished center member, means detachably securing said center member to said frame member, said center member and frame member each forming part of the outer wall of the cover, a second convex

dish shaped cover pivotally secured to said 35 ring member, said covers having their edges disposed in close relation when closed, and a toilet article directly retained by said center member.

11. In a vanity box, a cover comprising a 40 frame member having a thin inner edge and a separate center member having a thin outer edge, said members having substantially co-extensive walls overlapping at said thin edges to form a lap joint, means 45 detachably securing said center member to said frame member, said center member and frame member each forming part of the outer wall of the cover, a second cover pivotally connected to said frame member, and a 50 toilet compact molded in said center member.

12. A vanity case comprising a convex cover, said cover comprising a ring member and a separate convex dished center member 55 detachably connected thereto, said center member acting as the holder for a cosmetic compact, said ring member and center member, each forming part of the wall of the cover, and a cooperating convex cover detachably secured to said first cover, said covers meeting in a substantially thin edge 60 as compared to the maximum thickness of the case.

In testimony whereof I have hereunto 65 set my hand.

CHARLES N. CORYELL.
